OP D 12, 196

Mar. 22, 1881.

No. 12,196 S

Fig. I.

Fig. II.

Fig. III.

UNITED STATES PATENT OFFICE.

ROYAL E. WHITMAN, OF NEW YORK, N. Y.

DESIGN FOR A SADDLE.

SPECIFICATION forming part of Design No. 12,196, dated March 22, 1881.

Application filed November 11, 1880. Term of patent 14 years.

To all whom it may concern:

Be it known that I, ROYAL E. WHITMAN, a citizen of the United States, residing at New York city, State of New York, have invented 5 and produced a new and original Design for Saddles, of which the following is a specification, reference being had to the accompanying photographs, forming part thereof.

Figure I is a side elevation of my newly-de- 10 signed saddle. Fig. II is a top-plan view of the same, and Fig. III is a reverse-plan view, these three views being deemed necessary to fully illustrate my design.

Heretofore saddles have been made which 15 presented, when viewed in elevation, as in Fig. I, a high pommel combined with a high cantle formed of a prolongation of the bearing-surface, as in the Mexican saddle; of a pommel combined with a cantle rising abruptly 20 from the bearing-pads, as in the McClellan tree; and of a high pommel, of peculiar form, in combination with a high cantle, continued in an unbroken curve from the seat and set off from the upper surface of the ends of the bearing-pads, as shown in the design for saddle 25 for which patent was granted me, September 24, 1878, No. 10,844. But in the above-quoted patent the cantle, besides presenting the appearance of a high one for a saddle, in plan view, appears to be terminated in a tongue in 30 the medial line of the saddle, and in profile is continued to end in a reverse curve from that in which it rises from the seat; also, any view of this saddle, as in the case of any other heretofore made, shows a smooth top or seat surface.

The leading features of this design consist 35 in the combination, with the pommel, shaped as shown, of the low cantle, rising in an un- 40 broken curve from the lowest point of the seat until its profile in front and rear shows it to be clearly detached and raised from the upper surfaces of the ends of the bearing-pads, while the general appearance to the eye is of as low 45 and light a cantle as will suffice to keep the person of the rider in place upon the saddle, and of an unmistakable cantle offset from the bearing-pads, in contradistinction to the cantle prolonged upon the bearing-surface and built

up of padding, as in the ordinary jockey and 50 light training saddle. A profile view or side elevation shows the cantle to terminate at its highest point in the same curve in which it rises from the seat, and in plan view the cantle is shown rounded. 55

Another feature in my design for saddles consists in the recess defined by a curved line, 60 approximately portion of an ellipse, upon each side of the saddle-seat, with the foci of these curves at about the point where the stirrup-strap bars are ordinarily attached to the tree, the lines of which curves are defined by the shoulders of recesses made to receive the bars, and the recesses, when containing the bars, materially promote the appearance of light- 65 ness in the saddle.

A is the pommel, having its contour in profile defined by the line *a*, rising in a gradual curve from the lowest point, *a'*, of the seat to the highest point, *a''*, of the pommel. From 70 *a''* the line defining the contour of the pommel inclines outward and downward, and from *a'''* is rounded inward to the point *b*, where it joins the line *b'*, defining the bottom of the saddle and outlining the bearing-pads B. 75

C is the cantle, defined in contour by the line *c*, uniting at the lowest part of the seat to line *a'*, and by line *c'*, rising abruptly from the pads B, while the line *c*, defining the round cantle, joins the seat of the saddle at *c''*. 80

D are the approximately elliptical recesses upon the sides of the saddle.

By these lines an exceedingly graceful and light design for saddles is produced, and one essentially differing from any heretofore made. 85

In the photographic illustrations an uncovered tree is shown, the straps and bars, when added to complete the saddle, having no influence upon the design, and a covering, if applied, leaving its leading features unchanged. 90

The portion of this design forming the subject-matter of the second clause of claim is shown in the mechanical patent of date of January 25, 1881, No. 236,923, issued to the same inventor. 95

I claim—

1. The design for a saddle herein shown and described, the same consisting of the pom-

mel A, inclining outward and downward, and inclining inward to point b, pads B, and low rounded cantle C, when all combined and arranged substantially as set forth.

5 2. The design for a saddle herein shown and described, the same consisting of the recesses D D upon each side of the saddle, and

defined by curved edges, as shown and described.

ROYAL E. WHITMAN.
